(57) **CLAIM**

The ornamental design for a rechargeable tuner for musical instrument as shown and described.

DESCRIPTION

FIG. 1 is a top perspective view of a rechargeable tuner for musical instrument showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top elevation view thereof; and,

FIG. 7 is a bottom edge view thereof.

The broken lines in FIGS. 1-7 represent the portions of the rechargeable tuner for musical instrument which form no part of the claimed design.

1 Claim, 7 Drawing Sheets
